UNITED STATES PATENT OFFICE

96,497

DESIGN FOR A CLOTHES WRINGER

Raymond E. Patten, Bridgeport, Conn., assignor
to General Electric Company, a corporation of
New York

Application December 19, 1934, Serial No. 54,497

Term of patent 14 years

To all whom it may concern:

Be it known that I, Raymond E. Patten, a citizen of the United States, residing at Bridgeport, county of Fairfield, State of Connecticut, have invented a new, original, and ornamental Design for Clothes Wringers, of which the following is a specification, reference being had to the accompanying drawing, forming a part thereof.

Fig. 1 is a front perspective view of a clothes wringer showing my new design, the wringer being in the closed position.

Fig. 2 is a front perspective view of the clothes

wringer shown in Fig. 1, the wringer being in the open position.

The characteristic feature of my design resides in the blending of the drain boards with the wringer frame when in the closed position.

I claim:

The ornamental design for a clothes wringer, substantially as shown and described.

In witness whereof, I have hereunto set my hand this 13th day of Dec., 1934.

RAYMOND E. PATTEN.
